RAIL TIE AND ANCHOR

Sam Morano, Morgantown, W. Va.

Application February 15, 1939, Serial No. 256,539

4 Claims. (Cl. 238—331)

This invention relates to certain new and useful improvements in rail ties and anchors.

The primary object of the invention is to provide a rail tie and anchor especially designed for mine use wherein the tracks that are of a generally portable character may be quickly laid and removed into and through the tunnels of a mine.

A further object of the invention is to provide a novel construction of rail anchor devices that securely hold the rail in position on a tie and which may be easily and quickly operated for the placement or removal of a rail.

With the above and other objects in view that will become apparent as the nature of the invention is better understood, the same consists in the novel form, combination and arrangement of parts hereinafter more fully described, shown in the accompanying drawing and claimed.

In the drawing—

Figure 1 is a top plan view of a rail tie and anchor constructed in accordance with the present invention, the rail anchors being illustrated in their released positions;

Figure 2 is a top plan view showing the rail tie anchors in their rail engaging positions;

Figure 3 is a side elevational view of the tie with rails seated thereon and shown in section;

Figure 4 is a bottom plan view of the tie;

Figure 5 is an enlarged longitudinal detail sectional view taken on line 5—5 of Figure 2 with a rail added thereto showing the upper and lower mounting plates for the slidable rail clamp slidably supported upon the top wall of the tie;

Figure 6 is a fragmentary top plan view of one end of the tie with the slidable rail anchor supporting plates removed to illustrate the slotted construction of the tie for the support of the mounting plates; and

Figure 7 is a fragmentary top plan view of the tie with a modified form of slidable rail engaging clamps.

Referring more in detail to the accompanying drawing and particularly to Figures 1 to 6, there is illustrated a rail tie and anchor and while the same may be used for the laying of various types of tracks, the same is especially designed for use in mines. The tie comprises a flat top wall 10, having depending side flanges 11 of the desired depth and a lug 12 depending from each end of the top wall 10 for ground engagement to prevent longitudinal creeping of the tie.

Each end of the tie is constructed for the support of a rail 13 and the anchor means for each rail 13 includes a rail flange engaging clamp 14

rigid with and rising from the top wall 10 of the tie, cooperating clamps engageable with the other base flange of the rail being slidably associated with the tie and movable longitudinally of the tie and transversely of the rail.

In the form of invention shown in Figures 1 to 5 a pair of slidably mounted rail engaging clamps 15 is pivotally carried by a slidably mounted structure comprising a pair of rectangular plates 16 and 17 respectively disposed above and below the flat top wall 10 of the tie and flatly engaged therewith for sliding movements. As shown more clearly in Figure 6, the top wall 10 of the tie is provided with a pair of longitudinally slotted openings 18 respectively arranged adjacent and parallel to the side edges of the tie and an intermediate longitudinally extending slotted opening 19. A pair of headed bolts 20 extend upwardly through the outer end of the lower plate 17 adjacent the side edges thereof, through the slotted openings 18 for passage through fitting openings in the upper plate 16 for the reception of nuts 21 upon the upper threaded ends thereof. Another pair of headed bolts 22 extend upwardly through the inner end of the lower plate 17 adjacent opposite sides thereof for passage through the slotted openings 18, fitting openings in the upper plate 16 and through fitting openings in the rail clamps 15 affording pivotal supports therefor with nuts 23 threaded upon the upper ends of the bolts 22 as clearly shown in Figure 5. It will be seen that the bolts 20 and 22 maintain the upper and lower plates 16 and 17 in assembled relation and in sliding engagement with the top and bottom faces respectively of the flat top wall 10 of the tie. It will also be understood that the slidably mounted structure comprising the plates 16 and 17 that carry the rear engaging clamps 15 may be moved into binding engagement with the top wall 10 of the tie when the clamps 15 are engaged with the rails 13 by tightening the nuts 21 and 23 upon the bolts 20 and 22, respectively, the tightening of said nuts 21 and 23 causing the binding action of the upper and lower plates 16 and 17 upon the top wall 10 of the tie with the latter sandwiched between said plates as will be readily understood from an inspection of Figure 5. Therefore, the guide bolts 20 and 22 that hold the plates 16 and 17 in assembled relation may also be employed for moving the plates 16 and 17 into binding engagement with the tie for the anchoring of the slidable structure that supports the rail clamps 15.

To effect sliding movements of the plates 16

and 17 carrying the pivotally mounted rail engaging clamps 15, there is provided a block 24 rigid with the upper plate 16 and extending above the same as shown more clearly in Figure 5, 5 the block 24 having a portion 25 depending from the upper plate 16 and extending downwardly through the intermediate opening 19 in the top wall 10 of the tie for snug reception in an opening 25a formed in the lower plate 17 as shown 10 in Figure 4. The block 24 being rigid with the upper plate 16 and having the depending portion 25 thereof snugly received in an opening provided in the lower plate 17 provides an interlocking connection between said plates 16 and 15 17 to prevent relative movements of said plates longitudinally of the tie so that no strains or distorting movements can be imparted to the headed bolts 20 and 22. While the upper and lower plates 16 and 17 that carry the rail engaging clamps 15 are maintained in assembled 20 relation by the screw bolts 20 and 22, it is also intended to provide inwardly directed side flanges 26 on the lower edges of the side flanges 11 of the tie to underlie and support the opposite side 25 edges of the lower plate 17.

The rail anchor means is illustrated in Figure 1, as positioned for the reception of a rail, it being understood that the clamp arms 15 may be swung outwardly on their pivot bolts 22 30 and by engaging the block 21 by hand or with a suitable implement, the sliding plates 16 and 17 carrying the clamp arms 15 are moved toward the rail 13 and the clamping arms 15 swung into position for engagement with the adjacent side 35 of the base flange of the rail. When disposed as illustrated in Figure 2, the rail engaging clamps 15 and the sliding plates 16 and 17 are so retained by means of the cam arms 27 that are pivotally mounted upon the pins 28 on the top wall 19 of the tie by movement into engagement 40 with the outer edge of the upper plate 16 as shown in Figures 2, 3 and 5.

In lieu of the separate pivotally mounted clamping arms 15 shown in Figures 1 to 5, there may 45 be provided as shown in Figure 7, a clamp plate 15a secured to the sliding plates 16 and 17 by means of the bolts 22 with a rigid clamp arm 15b extending from each end of the clamp plate 15a in a direction toward the rigid rail engaging 50 clamp 14.

From the above detailed description of the invention, it is believed that the construction and operation thereof will at once be apparent, and while there are herein shown and described the 55 preferred embodiments thereof, it is nevertheless to be understood that minor changes may be made therein without departing from the spirit and scope of the invention as claimed.

I claim:

60 1. In a rail tie and anchor, a tie having a flat top wall and rail anchor means at each end of the top wall including a rail clamp rigid with the top wall and a cooperating rail clamp slidably mounted above the top wall, the mounting 65 for the sliding rail clamp including a pair of separate plates flatly engaged with and respectively disposed above and below the flat top wall and of substantially the same width as the tie with the flat top wall sandwiched therebetween, 70 said wall having longitudinally extending slotted openings therein and headed nut and bolt combinations connecting the upper and lower plates with the bolts extending through said slotted openings and adapted to move said plates 75 into binding engagement with the top wall of

said tie, said bolt being slideable in said longitudinally extending slots and carrying therewith said plates and the slideable rail clamp carried thereby.

2. In a rail tie and anchor, a tie having a flat top wall and rail anchor means at each end of the top wall including a rail clamp rigid with the top wall and a cooperating rail clamp slidably mounted above the top wall, the mounting 10 for the sliding rail clamp including a pair of separate plates flatly engaged with and respectively disposed above and below the flat top wall and of substantially the same width as the tie with the flat top wall sandwiched therebetween, 15 said wall having longitudinally extending slotted openings therein and headed nut and bolt combinations connecting the upper and lower plates with the bolts extending through said slotted openings and adapted to move said plates into binding engagement with the top wall of said tie, said bolt being slideable in said longitudinally extending slots and carrying therewith said plates and the slideable rail clamp carried thereby, said flat top wall having a longitudinally extending 20 slotted opening therein between the aforesaid 25 openings and means to facilitate manual shifting of said mounting plates and to retain said plates against relative longitudinally shifting movements including a block rigid with the top plate with a portion projecting above the same 30 and said block having a depending portion extending downwardly through said intermediate opening and having a snug interfitting engagement with the lower mounting plate.

3. In a rail tie and anchor, a tie having a flat top wall and rail anchor means at each end of the top wall including a rail clamp rigid with the top wall and a cooperating rail clamp slidably mounted above the top wall, the mounting 35 for the sliding rail clamp including a pair of separate plates flatly engaged with and respectively disposed above and below the flat top wall and of substantially the same width as the tie with the flat top wall sandwiched therebetween, 40 said wall having longitudinally extending slotted openings therein and headed nut and bolt combinations connecting the upper and lower plates with the bolts extending through said slotted openings and adapted to move said plates into binding engagement with the top wall of 45 said tie, said bolt being slideable in said longitudinally extending slots and carrying therewith said plates and the slideable rail clamp carried thereby, said flat top wall having a longitudinally extending slotted opening therein between the aforesaid 50 openings and means to facilitate manual shifting of said mounting plates and to retain said plates against relative longitudinally shifting movements including a block rigid with the top plate with a portion projecting above the same 55 and said block having a depending portion extending downwardly through said intermediate opening and having a snug interfitting plate, and said slideable rail clamp including a pair of pivotally mounted clamp arms respectively carried by opposite sides of the upper mounting plate.

4. In a rail tie and anchor, a tie having a flat top wall and rail anchor means at each end of the top wall including a rail clamp rigid with the top wall and a cooperating rail clamp slidably mounted above the top wall, the mounting 70 for the sliding rail clamp including a pair of separate plates flatly engaged with and respectively disposed above and below the flat top wall 75

and of substantially the same width as the tie with the flat top wall sandwiched therebetween, said wall having longitudinally extending slotted openings therein and headed nut and bolt combinations connecting the upper and lower plates with the bolts extending through said slotted openings and adapted to move said plates into binding engagement with the top wall of said tie, said bolt being slidable in said longitudinally extending slots and carrying therewith said plates and the slidable rail clamp carried thereby, said flat top wall having a longitudinally extending slotted opening therein between the aforesaid openings and means to facilitate manual shift-

ing of said mounting plates and to retain said plates against relative longitudinally shifting movements including a block rigid with the top plate with a portion projecting above the same and said block having a depending portion extending downwardly through said intermediate opening and having a snug interfitting engagement with the lower mounting plate, the slidably mounted rail engaging clamp being of one-piece construction and having a central cut-away portion to provide a pair of spaced end clamping arms.

SAM MORANO.
